HOOD ORNAMENT FOR AN AUTOMOBILE

Charles F. Gitschlag, Jr., St. Clair Shores, Mich., assignor to Chrysler Corporation, Highland Park, Mich., a corporation of Delaware

Application June 11, 1956, Serial No. 41,858

Term of patent 7 years

(Cl. D14—18)

Fig. 1 is a side elevational view of a hood ornament for an automobile showing my novel design;

Fig. 2 is a plan view thereof;

Fig. 3 is a front elevational view thereof;

Fig. 4 is a sectional view taken on the line 4—4 of Fig. 2; and

Figs. 5, 6, 7, 8 and 9 are sectional views taken on the lines 5—5, 6—6, 7—7, 8—8 and 9—9, respectively, of Fig. 1.

I claim:

The ornamental design for a hood ornament for an automobile, substantially as shown.
